UNITED STATES PATENT OFFICE.

JAMES W. ARROWSMITH, OF MORRISTOWN, NEW JERSEY, ASSIGNOR TO ARROWSMITH MANUFACTURING COMPANY, A CORPORATION OF NEW JERSEY.

ARCH-SUPPORT.

1,077,864.

Specification of Letters Patent.

Patented Nov. 4, 1913.

Application filed February 17, 1909. Serial No. 478,461.

To all whom it may concern:

Be it known that I, JAMES W. ARROWSMITH, a citizen of the United States, and a resident of the city of Morristown, in the 5 county of Morris and State of New Jersey, have invented certain new and useful Improvements in Arch-Supports, of which the following is a specification.

My invention relates to supports for the 10 arch of the human instep, used ordinarily for the relief and cure of what is commonly called "flat-foot." Its objects are, among others, to provide a simple strong and effective support which may be adjusted to 15 fit different feet and to correct deformity from time to time, and which will retain its shape and resist the weight imposed upon it and the tendency toward crystallization of the metal which almost invariably terminates the usefulness of supports of this character.

It also has for one of its objects the provision of a comparatively rigid portion at the apex of the arch which is beneath the 25 astragalus, while at the same time providing a sufficient area of resilient and flexible metal to give the device a proper spring and permit adjustment.

The improvements consist in the construction 30 and combination of parts herein described and illustrated in the accompanying drawings.

In the said drawings Figure 1 is an underside view of an instep support embodying the improvements. Fig. 2 is a vertical medial section on the line 2-2 of Fig. 1. Fig. 3 is a longitudinal section on the line 3-3 of Fig. 1.

The plate A is approximately triangular 40 in form and is designed to fit the cavity of the plantar fascia between the protuberance of the calcaneum and the metatarsal bones. It has a turned up portion at its inner edge provided with slits A' arranged substantially 45 on radial lines drawn from the point A² at the opposite side, which slits divide the turned up portion into fingers which may be adjusted according to the position of the bones at the apex of the arch and particularly 50 the astragalus, navicular and cuneiform bones.

The substantially triangular plate A is superimposed upon the plate B of substantially 55 spatulate form adapted to extend from a point beneath the os-calcis to the anterior

end of the first metatarsal, both plates being arranged in such a manner that the upper surface presented by them conforms to the arch of the instep from end to end and from side to side. They are joined together by 60 rivets or other fastenings D located at the front and rear extremities respectively of the plate A and near the inner edge of the plate B between the curved rib C and the said edge. The cover E of non-metallic material 65 is also secured to the plates by the same fastenings.

The rib or boss C extends longitudinally of the plate B and gradually merges in the said plate at its ends, which ends are located 70 beneath the edges of the plate A. This rib has a widened part at its center and at the apex of the arch of the plate, extending in the direction of the point A² of the plate A. The other edge of the rib is preferably an 75 uninterrupted curve.

The form and arrangement of the two plates and the rib C are of great importance to the desired results, and while they may be varied within certain limits without departing from the spirit of the invention, the anatomical requirements of the support necessitate substantial adherence to the features of construction and arrangement of these parts with respect to each other hereinafter claimed. The plate A may be made to conform to the cavity of the plantar fascia, but owing to the fact that it has no portion extending beyond this cavity it cannot support itself in an elevated position nor 80 be adjusted to meet different conditions of the foot, and the plate B therefore becomes necessary to elevate the plate A and provide for this vertical adjustment as well as the adjustment of this portion with respect to 85 the horizontal. Again it is not in all cases desirable to make the portion of the instep support represented by the plate A integral with the extending portion, as when so constructed some of the adjustments tend to 90 render the position of this portion of the support with respect to the bones forming the upper part of the arch incorrect. By forming the plates A and B, as shown and mounting the former on the latter I am enabled to maintain the correct position and 95 adjustment of the portion of the plate beneath the upper arch and at the same time adjust it in various ways, adjust the portion 100 of the support beneath the lower part of the 105

arch and, also adjust the upper plate when desired, without having the adjustment of one interfere with the other.

Other important features of the construction and arrangement are the fastenings and the rib C, especially the latter. By providing this rib beneath the plate A, extending longitudinal of the plate B more strength and rigidity are provided where such strength and rigidity are most needed, and by extending the rib at its center and apex of the arch in the direction of the outer side additional strength is provided at this point and at the same time a check or barrier is provided which will effectively interrupt crystallization and intercept the weakened lines resulting therefrom, which, in time would end in the cracking and breaking down of the plate. The location and form of this rib are such that it does not interfere with necessary adjustment of the resiliency of the support, and the ends of the rib merging in the surface of the plate B not only permit a gradual increase in resiliency toward the ends of the plate but prevent crystallization and cracking at these parts.

What I claim is:

1. The combination of a plate curved to approximate the arch of the instep and extending from the calcaneum to the anterior metatarsus, and a longitudinal rib or boss in the medial portion of said plate having an enlargement at the center extending in the direction of the outside of the foot.

2. The combination of a plate curved to approximate the arch of the instep and extending from the calcaneum to the anterior metatarsus, a longitudinal rib or boss in the medial portion of said plate having an enlargement at the center extending in the direction of the outside of the foot, and a second plate also arched to fit the instep superimposed upon the first plate having its forward and rear edges near the ends of said rib.

3. The combination of a plate curved to approximate the arch of the instep and extending from the calcaneum to the anterior metatarsus, a longitudinal rib or boss in the medial portion of said plate having an

enlargement at the center extending in the direction of the outside of the foot, and a second plate also arched to fit the instep superimposed upon the first plate having its forward and rear edges near the ends of the said rib, and a connection between the two plates located between the rib and the inner edge of the first named plate.

4. The combination of a plate curved to approximate the arch of the instep and extending from the calcaneum to the anterior metatarsus, and a longitudinal rib or boss in the medial portion of said plate having an enlargement at the center extending in the direction of the outside of the foot, the said rib increasing in depth toward the center.

5. The combination of a plate curved to approximate the arch of the instep and extending from the base of the heel to the ball of the foot, a second plate extending from a point forward of the base of the heel to a point short of the ball of the foot, the said first named plate being provided with a longitudinal rib or boss corresponding substantially with the width of the said second plate.

6. The combination of a plate curved to approximate the arch of the instep and extending from the base of the heel to the ball of the foot, a second plate extending from a point forward of the base of the heel to a point short of the ball of the foot, the said first named plate being provided with a longitudinal rib or boss corresponding substantially with the width of the said second plate, said rib having an enlargement near the middle of the first named plate.

7. The combination of a plate curved to approximate the arch of the instep and extending from the calcaneum to the anterior metatarsus, and a longitudinal rib or boss in the medial portion of said plate having a lateral enlargement at the center.

Witness my hand this 15th day of February, 1909.

JAMES W. ARROWSMITH.
